Primary Examiner — Michelle E. Wilson*Assistant Examiner* — Richard E Yenchesky(74) *Attorney, Agent, or Firm* — Birch, Stewart, Kolasch & Birch, LLP(57) **CLAIM**

We claim the ornamental design for a shoe care device, as shown and described.

DESCRIPTION

FIG. 1 is a perspective view of a shoe care device showing the new design:

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view showing the inside of the door thereof; and,

FIG. 9 is a perspective view showing a state of use thereof. The parts shown by means of broken lines in the drawing figures are not part of the claimed design.

1 Claim, 9 Drawing Sheets(56)
